190,536

CAP FOR A STAPLING MACHINE OR
SIMILAR ARTICLE

Henry Ruskin, Bayside, N.Y., assignor to Swingline, Inc.,
Long Island City, N.Y., a corporation of New York

Filed Apr. 19, 1960, Ser. No. 60,252

Term of patent 14 years

(Cl. D74—1)

FIG. 1

FIG. 2

FIG. 3

FIG. 4

FIG. 5

FIG. 6

FIG. 1 is a side perspective view of a cap for a stapling machine showing my new design, the broken line illustration of a stapling machine being for illustrative purposes only;

FIG. 2 is a top plan view of the cap for a stapling machine shown in solid lines in FIG. 1;

FIG. 3 is a front elevational view thereof;

FIG. 4 is a side elevational view thereof;

FIG. 5 is a rear elevational view thereof; and

FIG. 6 is a sectional view thereof taken on the line 6—6 of FIG. 2.

I claim:

The ornamental design for a cap for a stapling machine or similar article, as shown and described.
